UNITED STATES PATENT OFFICE.

CARL LUDWIG HRAUDA, OF CROUCH END, ENGLAND.

COMBINED BOOK-MARKER AND LEAF-HOLDER.

SPECIFICATION forming part of Letters Patent No. 756,115, dated March 29, 1904.

Application filed July 18, 1902. Serial No. 116,078. (No model.)

To all whom it may concern:

Be it known that I, CARL LUDWIG HRAUDA, a subject of the King of Great Britain, residing at Crouch End, in the county of Middlesex, England, have invented certain new and useful Improvements in a Combined Book-Marker and Leaf-Holder; and I do hereby declare the following to be a full, clear, and exact description of the invention, such as will enable others skilled in the art to which it appertains to make and use the same.

This invention relates to a combined book-marker and leaf-holder which may be either temporarily or permanently affixed to the book-cover for the purpose of holding down the leaves (particularly those on the right) while reading and of marking the place when the book is closed.

In order that my invention may be more readily understood, I have caused to be attached hereto one sheet of drawings, in which similar letters refer to similar parts.

Figures 1 and 2 show the face and edge of the device, and Fig. 3 shows the shape of clip for temporarily fastening the device to cover.

The device consists of a clip A, which may be either permanently attached to any book-cover by means of rivets or any other similar method, or for temporary attachment the clip A may be provided with spring B, in which case the said clip can be slipped onto any book-cover, where it will be held firm by means of the said springs B. The springs B are preferably spooned out at the end to prevent injury to the cover of the book. Projecting from the clip A is an arm C, with end D bent at right angles, as shown in Fig. 1. At the angle between the arm C and D it is preferable to form a projection E, as shown in Fig. 1, to prevent the leaves of the book being torn; but, if desired, the angle may be formed with a

plain bend. The end of D is spoon-shaped to prevent injury to the leaves of the book.

It will be readily seen that the device may be stamped out of a flat sheet of material, a projection F, as shown in dotted line in Fig. 1, being stamped out at the same time and afterward bent round to form the clip A, as shown in Fig. 3.

The device will be preferably made from sheet metal, such as sheet-steel, sheet-brass, and the like; but other suitable materials may also be used, such as celluloid, ebonite, and the like.

The device is used as follows: The clip is slipped over the cover of the book, preferably on the right-hand side, and firmly held, as previously described. The arm D is then placed over any desired page, thus forming a leaf-holder. The leaves may be slipped from under the said arm D as required. On shutting the book the arm D remains between the pages ready for opening the book at the last page read.

Having now particularly described and ascertained the nature of my said invention and in what manner the same is to be performed, I declare that what I claim is—

A combined book-mark and leaf-holder, composed of a flat strip of elastic metal C having one end bent over to form a clip A having parallel walls or sides, springs B beneath the clip and the lateral extension D, located in substantially the same plane as the part C and adapted to hold the leaves of a book substantially as described.

In testimony whereof I affix my signature in presence of two witnesses.

CARL LUDWIG HRAUDA.
